US00D966338S

(12) **United States Design Patent** (10) **Patent No.:** **US D966,338 S**
Johnson (45) **Date of Patent:** **** Oct. 11, 2022**

(54) **PORTION OF A DISPLAY SCREEN WITH ICON OF A ROBOTIC ARM**

(71) Applicant: **Verb Surgical**, Mountain View, CA (US)

(72) Inventor: **Eric Johnson**, Pacific Grove, CA (US)

(73) Assignee: **Verb Surgical Inc.**, Mountain View, CA (US)

(**) Term: **15 Years**

(21) Appl. No.: **29/766,875**

(22) Filed: **Jan. 25, 2021**

(57) **CLAIM**

The ornamental design for a portion of a display screen with icon of a robotic arm, as shown and described.

DESCRIPTION

FIG. 1 is a front view of a portion of a display screen with icon of a robotic arm; and, FIG. 2 is a front view of a portion of a display screen with icon of a robotic arm of FIG. 1, in which a remote control of a robotic surgical system in broken lines is provided to illustrate an example environment.

The broken line drawing showing of a display screen in FIG. 1 and a display screen and device in FIG. 2 is included for the purpose of showing portions of the article which form no part of the claim.

1 Claim, 2 Drawing Sheets
